(57) **CLAIM**

The ornamental design for an egg processing tool, as shown and described.

DESCRIPTION

FIG. 1 is a top perspective view of the egg processing tool showing my new design.

FIG. 2 is a bottom perspective view thereof.

FIG. 3 is a top plan view thereof.

FIG. 4 is a bottom plan view thereof.

FIG. 5 is a left side view thereof.

FIG. 6 is a right side view thereof.

FIG. 7 is a front view thereof.

FIG. 8 is a rear view thereof.

FIG. 9 is a top perspective view thereof, the broken lines are for the purpose of illustrating the structure and form no part of the claimed design; and,

FIG. 10 is a perspective view of the assembly of FIG. 9. The broken lines are included for the purpose of illustrating portions of the structure that form no part of the claimed design.
